UNITED STATES PATENT OFFICE.

EDWARD H. HELT, OF BELLEVUE BOROUGH, PENNSYLVANIA.

COIN-OPERATED MECHANISM.

1,347,742.

Specification of Letters Patent.

Patented July 27, 1920.

Application filed November 4, 1919. Serial No. 335,577.

To all whom it may concern:

Be it known that I, EDWARD H. HELT, a citizen of the United States, and residing in the borough of Bellevue, county of Allegheny, and State of Pennsylvania, have invented or discovered certain new and useful Improvements in Coin-Operated Mechanism, of which the following is a specification.

My invention consists in certain new and useful improvements in the coin operated mechanism of automatic vending machines.

One object which I have in view is the provision of means whereby such mechanism may be set or adjusted to operate with different numbers of the proper coin, thereby enabling the mechanism to be set for vending articles of different values. Thus by setting the machine properly articles of, say the value of five cents can at one time be vended, while at another time ten cent, fifteen cent, twenty cent article or articles of any other desired value in multiples of five cents may be vended.

My improved mechanism can be set to operate upon the insertion of one or any larger number, within a reasonable range, of the proper coin.

Generally speaking, my mechanism is characterized by a moving member which is so connected to the vending machine that the latter is operated when the member is moved in the proper direction. Means are provided which automatically lock the member against the required movement, such means being however rendered inactive by the insertion of the proper coin or coins in the mechanism, the locking means being adjustable so that it may be set to require any given number of coins in the mechanism to render it operable.

I also show novel means whereby the actuating element of a coin operated mechanism is normally locked against actuating movement and the locking mechanism is rendered inactive by the insertion of a coin or coins.

Other novel features of construction and arrangement of parts will appear from the following description.

In the accompanying drawings, which are merely intended to illustrate a practical embodiment of the principle of my invention without limiting the scope of the same to the construction shown, Figure 1 is a front elevation of my mechanism shown contained

in an outer box or case; Fig. 2 is a vertical section of the mechanism; Fig. 3 is a bottom plan view of the mechanism, the lever shown for connecting the mechanism to a vending machine, being shown in section; Fig. 4 is a broken rear elevation of the mechanism shown in its position of rest; Fig. 5 is an enlarged side elevation showing the mechanism at rest with the proper number of coins inserted; Fig. 6 is a broken side elevation showing the slide depressed when it operates the vending machine; permitting the coins to drop out of the coin slot; and Fig. 7 is a broken vertical section showing an insufficient number of coins in the slot and the mechanism locked when an attempt is made to depress it.

The following is a detailed description of the drawings.

A is the box or outer case, preferably made of metal and provided with a front panel 1 of glass. B is the back or supporting plate rigidly mounted in the case A, as by brackets 2. 3 represents vertically disposed rails fixed to the back of plate B between which works the slide bar C which is provided with a longitudinal coin slot 4, open at the bottom and also, preferably, at the top of the slide. The slide C is held in position between the rails as by the cross bar 5 near the upper ends of the rails and the inwardly extending plates 6 secured to the rails near their bottom ends.

7 represents plates secured to the outer faces of the rails and shown extending below the latter. Said plates are provided on their exposed edges with locking notches 8 whose lower walls are horizontal while their upper walls are inclined to form entrances to said notches. The notches on the two lock plates 8 are aligned horizontally in pairs, and the number of pairs provided equals the greatest number of coins which the mechanism can be set to require to make the same operate.

The plate B is provided with a longitudinal slot 9 and the front wall of the slide C is provided with a similar slot 10 which registers with slot 9 when the slide is elevated. The slot 10 thus exposes a portion of the interior of the coin slot 4 through the slot 9, so that the coins in said slot 4 can be seen through the glass front of the case A. The rear wall of the slide C, opposite the slot 10 in its front wall, is provided with a vertical row of pin holes 11 which are in effect ex-

tended rearwardly of the slide by means of annular collars or slide bearings 12 fixed on the rear face of the slide.

D is an open frame fixed on the rear face 5 of the slide C and consisting of end cross bars 13 attached to the slide and having their ends connected by side plates 14 which move outside of the notched plates 7. The plates 14 are provided in the horizontal 10 plane of each pin hole 11 with slots 15 extending outwardly from their inner edges to a distance greater than the width of the lock plates 7. 16 represents a central longitudinal bar on the frame D provided with a 15 series of pin holes 17, one in the same horizontal plane of each of the pin holes 11 and corresponding pairs of slots 15. 18 represents pins whose inner ends engage the bearings 12 while their outer ends protrude 20 through the holes 17 in the bar 16. 19 are cross heads fixed on the pins 18, and 20 are helical springs coiled about said pins between said cross heads and the bar 16, thus tending to force said pins through the holes 25 11 into the coin slot 4. Said pins may be held retracted from said coin slot by means of washers 21 and nuts 22 on the outer ends of said pins. In the drawings I have shown the two upper pins and the bottom pin thus 30 retracted, while the second pin from the bottom is not thus retracted and may be termed "active."

The slide C and the frame D are normally held elevated by the helical spring 23 which 35 connects the top of the frame with a point on the plate B near its top. After the slide is depressed, when released, it will thus be automatically returned to its elevated position.

40 24 is a second vertical slot in the plate B, below the slot 9, or the two slots may be continuous. The lower end of the slide C is also slotted transversely to the coin slot and is provided with a pair of spaced apart projections 25 which protrude through the slot 45 24 and by contacting with the lower end of said slot, limit the downward movement of the slide C. The projections 24 are pierced to permit the lever 26 to be pivoted between 50 them, the short end of said lever normally occupying the slotted lower end of the slide C, intersecting the coin slot 4 and preventing the downward escape of the coins E contained in said coin slot. 27 is an abutment 55 bar spaced from and mounted on the plate B at the lower end of the slot 24, and 28 is a helical spring connecting the outer and longer end of the lever 26 to the abutment 27, thus holding the lever in its horizontal 60 position, when the slide C is elevated, to block the lower end of the coin slot 4.

The upward movement of the slide C and frame D is limited by any convenient means, such as the contact of the heads of screws

29 on the slide with the under side of the 65 cross bar 5.

The position of the slide and frame when elevated and at rest is such that the cross heads 19 of the pins 18 are just above the corresponding notches 8 in the lock plates 7. 70

30 is a lever or other operative connection attached to the lower end of the slide C in any convenient manner, and adapted, when the slide is depressed, to actuate the vending machine not shown. 75

It is evident that many different types of operative connection between the sliding elements of my coin operated mechanism and a vending machine may be used. This operative connection is therefore simply indicated 80 by the depending lever 30 extending through a slot 31 in the bottom of the case A.

32 is a push stem attached to the upper end of the slide and extending up through a slot 33 in the top of the case A. A convenient manner of securing the push stem to the slide is by inserting the former into the upper end of the coin slot 4 and securing it to the slide by screws 34. 85

35 is a coin hopper on the top of the case 90 A communicating with a curved passage 36, formed on the back of plate B. 37 is a lateral gate or entrance to the coin slot 4, so positioned that when the slide C is in its elevated position, said gate registers with 95 the lower end of the passage 36, so that the proper coin, when inserted in the hopper 35 will pass down into the coin slot 4 and rest on the inner end of the lever 26 or upon the coin previously inserted, as the case may be. 100

The side of the passage 37 is preferably slotted, as at 38 to permit a coin of too small a diameter to drop out laterally to the bottom of the case A without entering the coin slot 4. 105

The operation of my improved coin mechanism, as the same is illustrated in the accompanying drawings is as follows:

It will be noted in the drawings that the second pin 18 from the bottom is not permanently retracted and thus may for convenience be called active. Thus the mechanism is set or adjusted to require the insertion of two coins, say nickles, before the slide C can be depressed to operate the associated vending machine, not shown. 110

It will be seen that when the mechanism is at rest, as in Fig. 5, said active pin 18 is held retracted by the contact of its cross head 19 with the unnotched portions of 115 the edges of the lock plates 7.

If there is less than two coins E in the lower end of the coin slot 4, then an attempt to depress the slide C by forcing down on the push stem 32 will simply result in the 120 cross head 19 being sprung into engagement with the adjacent pair of locking notches 8, thus locking the slide C against further 125

depression and preventing the operation of the vending machine. This action is shown in Fig. 7 where the active pin 18 has been forced to protrude into the slot 4 and the 5 cross head is engaged with the locking notches.

However, if, as in Fig. 5, the necessary two coins E are inserted in the slot, when the push rod is forced downwardly, the 10 cross head 19 of the active pin 18 will not be sprung into engagement with the locking notches 8 because the upper coin blocks the corresponding pin hole 11 in the wall of the slide C, thus holding the active pin 15 retracted so that its cross head will pass down in front of the notches 8 without engaging the same, and thus the slide can be depressed until its projections 25 contact with the lower end of the slot 24 in the 20 plate B. Thus the vending machine is operated. When the slide C reaches the lower end of its movement, the lever 26 contacts with the abutment 27 and is tilted, as shown in Fig. 6, permitting the coins E to drop 25 out at the bottom of the slot into the case A.

Of course, the distance from the top edge of the lever 26, when the same is horizontal to the first pin hole 11 and the distances between the pin holes must be sufficient to 30 properly position the coins in the slot 4. Thus said pin holes should be centered apart a distance equal to the diameter of the coin intended to be used while the distance from the center of the lowest pin 35 hole to the top edge of the lever should be equal to half the diameter of the coin, so that a coin will seal the pin hole by its center.

Where articles to the value of a single 40 coin of the determined size are to be vended, then all of the pins 18 would be held retracted by means of the nuts and washers except the lowermost pin which would be active, locking the mechanism against operative movement unless a coin was first inserted in the slot 4. With the coin inserted, the same would hold the active pin retracted and permit the full depression of the slide.

50 If three coins are to be required, the second pin from the top would be made active and the rest inactive. If four coins are to be required, the top pin would be made active and the remainder may be inactive. 55 By increasing the number of pins 18, pin holes 11, and pairs of locking notches 8, it is evident that the machine might be set to operate with the insertion of any desired number of coins.

60 When the stem 32 is relieved of pressure the spring 23 automatically returns the slide and frame to its elevated position at rest. This occurs in case a full operative depression has just been effected or an attempt has been 65 made to operate the mechanism with an in-

sufficient number of coins resulting in locking the mechanism as above described.

It is evident from the foregoing that my invention provides a coin operated device which may be adjusted or set for the vending of articles of greater or less value. This is a very important and advantageous feature, especially in automatic restaurant service where articles of a large range of values are for sale. Thus the coin operated 70 mechanism may be standard in construction and the individual mechanism set for the proper values of the particular articles whose sale they are to control.

The mechanism is simple, durable and 80 easy to keep in efficient working order. The coins which are inserted in the slot are in plain view until discharged simultaneously with the operation of the vending machine, so in case of a dispute owing to the refusal of the mechanism to work, the coins inserted by the customer can be easily seen and counted.

Although, for the sake of clearly illustrating the principles of my invention, I 90 have minutely described the embodiment shown in the drawings, I do not wish to limit myself thereby but claim broadly:

1. In a coin operated mechanism adapted to be operated with different numbers of 95 coins, the combination of a fixed member, an actuating member provided with a longitudinally disposed coin slot into which the coins are dropped one after the other and mounted to reciprocate in relation to 100 said fixed member, a plurality of locking means moving with said actuating member and individually adapted to engage a portion of said fixed member to prevent actuating movement of said actuating member, 105 means for rendering said locking means individually inactive, and means whereby the active locking means are temporarily rendered inoperative by the insertion of the proper number of coins in said coin slot, 110 thereby permitting the actuating movement of said actuating member.

2. In a coin operated mechanism adapted to be operated with different numbers of 115 coins, the combination of a fixed member, an actuating member provided with a longitudinally disposed coin slot into which the coins are dropped one after the other and mounted to reciprocate in relation to said fixed member, a plurality of locking means 120 moving with said actuating member and individually adapted to engage a portion of said fixed member to prevent actuating movement of said actuating member, means for rendering said locking means individually inactive, means whereby the active locking means are rendered temporarily inoperative by the insertion of the proper number of coins in said coin slot, thereby 125 permitting the actuating movement of said 130

actuating member, and means whereby said coins are discharged from said coin slot upon the actuating movement of said actuating member.

5 3. In a coin operated mechanism adapted
to be adjusted to operate with different
numbers of coins, the combination of a
fixed member, an actuating member pro-
vided with a longitudinally disposed coin
10 slot into which the coins are dropped one
after the other and mounted to recipro-
cate in relation to said fixed member, a
plurality of individual locking means adapt-
ed to prevent the actuating movement of
15 said actuating member, means whereby any
selected locking means may be rendered
temporarily inactive by the insertion of the
proper number of coins in said coin slot,
and additional means for rendering the re-
20 mainder of said locking means inoperative,
whereby all but the selected locking means
are inoperative while the actuating mem-
ber may be released for operation by the
25 insertion of the proper number of coins in
said coin slot.

4. In a coin operated mechanism adapted to be adjusted to operate with different numbers of coins, the combination of a fixed member, an actuating member provided with a longitudinally disposed coin slot into which the coins are dropped one after the other and mounted to reciprocate in relation to said fixed member, a plurality of individual locking means adapted to prevent the actuating movement of said actuating member, means whereby any selected locking means may be rendered temporarily inactive by the insertion of the proper number of coins in said coin slot, additional means for rendering the remainder of said locking means inoperative, whereby all but the selected locking means are inoperative while the actuating member may be released for operation by the insertion of the proper number of coins in said coin slot, and means whereby the coins are discharged from said coin slot upon the actuating movement of said actuating member.

50 5. In a coin operated mechanism adapted to be adjusted to operate with different numbers of coins, the combination of a fixed member, an actuating member provided with a longitudinally disposed coin slot into
55 which the coins are dropped one after the other and mounted to reciprocate in relation to said fixed member, a plurality of devices each adapted to lock said actuating member against actuating movement, means
60 whereby each of said locking devices may be individually rendered temporarily inactive by the insertion of the proper number of coins in said coin slot, and additional means for individually rendering said locking

means inoperative, whereby all but a selected one of said locking devices may be rendered inoperative by said last named means and the actuating member may then be released for actuating movement by the insertion of the proper number of coins in said coin slot. 65 70

6. In a coin operated mechanism adapted to be adjusted to operate with different numbers of coins, the combination of a fixed member, an actuating member provided with a longitudinally disposed coin slot into which the coins are dropped one after the other and mounted to reciprocate in relation to said fixed member, a plurality of devices each adapted to lock said actuating member against actuating movement, means whereby each of said locking devices may be individually rendered temporarily inactive by the insertion of the proper number of coins in said coin slot, additional means for individually rendering said locking means inoperative, whereby all but a selected one of said locking devices may be rendered inoperative by said last named means and the actuating member may then be released for actuating movement by the insertion of the proper number of coins in said coin slot, and means whereby the coins are discharged from said coin slot upon the actuating movement of said actuating member. 75 80 85 90 95

7. In a coin operated mechanism adapted to be adjusted to operate with different numbers of coins, the combination of a fixed member, an actuating member provided with a longitudinally disposed coin slot into which the coins are dropped one after the other and mounted to reciprocate in relation to said fixed member, an actuating member provided with a coin slot and mounted to reciprocate in relation to said fixed member, a plurality of devices moving with said actuating member, and each adapted, by engagement with a portion of said fixed member, to lock said actuating member against actuating movement, means whereby each of said locking devices may be rendered temporarily inactive by the insertion of the proper number of coins in said coin slot, and additional means for individually rendering said locking means inoperative, whereby all but a selected one of said locking devices may be rendered inoperative by said last mentioned means, and the actuating member may then be released for actuating movement by the insertion of the proper number of coins in said coin slot. 100 105 110 115 120

8. In a coin operated mechanism adapted to be adjusted to operate with different numbers of coins, the combination of a fixed member, an actuating member provided with a longitudinally disposed coin slot into which the coins are dropped one

- after the other and mounted to reciprocate in relation to said fixed member, a plurality of devices moving with said actuating member, and each adapted, by engagement with 5 a portion of said fixed member, to lock said actuating member against actuating movement, means whereby each of said locking devices may be rendered temporarily inactive by the insertion of the proper number 10 of coins in said coin slot; additional means for individually rendering said locking means inoperative, whereby all but a selected one of said locking devices may be rendered inoperative by said last mentioned 15 means and the actuating member may then be released for actuating movement by the insertion of the proper number of coins in said coin slot, and means whereby the coins are discharged from said coin slot upon the 20 actuating movement of said actuating member.
9. In a coin operated mechanism, the combination of a fixed support, an actuating member mounted to reciprocate in parallel 25 relation to said support, a coin slot having a lateral opening in the wall thereof, and a spring detent adapted to lock said member against actuating movement, said detent when in its locking position protruding 30 transversely through said opening into said slot, whereby when a coin is inserted in said slot said detent is held retracted by contact with the flat face of said coin.
10. In a coin operated mechanism, the combination of a fixed support, an actuating member provided with a coin slot and in reciprocating relation to and parallel with said support, said coin slot being provided with a lateral opening in its wall, and a spring detent adapted to lock said member 35 against actuating movement, said detent when in its locking position protruding transversely through said opening into said slot, whereby when a coin is inserted in said slot said detent is held retracted by 40 contact with the flat face of said coin.
11. In a coin operated mechanism, the combination of a fixed support, an actuating member movable in relation to said support, a coin slot having lateral openings in 45 the wall thereof, a plurality of spring detents individually adapted to lock said member against actuating movement, said detents when in their locking positions protruding through said openings in said slot 50 whereby coins properly positioned in said slot will hold said detents retracted, and additional means for holding selected detents in their retracted positions.

Signed at Pittsburgh, Pa., this 29th day 60
of October, 1919.

EDWARD H. HELT.
